UNITED STATES PATENT OFFICE.

SAMUEL MASON, OF HAMDEN, CONNECTICUT.

IMPROVEMENT IN CARRIAGE-POLE TIPS.

Specification forming part of Letters Patent No. **145,885**, dated December 23, 1873; application filed April 16, 1873.

To all whom it may concern:

Be it known that I, SAMUEL MASON, of Hamden, in the county of New Haven and State of Connecticut, have invented a new Improvement in Pole-Crab for Carriages; and I do hereby declare the following, when taken in connection with the accompanying drawings and the letters of reference marked thereon, to be a full, clear, and exact description of the same, and which said drawings constitute part of this specification, and represent, in—

Figure 1, a side view, and in Fig. 2 a sectional view.

This invention relates to an improvement in what is known as a "carriage-pole crab"—that is to say, the tip for the end of the pole. This has usually been formed by forging, and made in several parts, riveted or welded together, hence making this an expensive part of the carriage-ironing, and which is usually done by the carriage-smith. The object of this invention is to produce a tubular tip, upper and lower straps, the tip-eye, and holdback ready for the carriage-maker to apply, and at a greatly-reduced price; and it consists in forming the tubular tip, upper and lower straps, the tip-eye, and holdback complete, in a single piece, from malleable cast metal.

A is the tubular portion or tip; B, the upper and C the lower strap to run back onto the

pole. An eye, D, is formed at the forward end, and beneath an arm, E, projects downward to form a shoulder for the holdback, and with a brace, F, running back from the said arm.

This article is molded and cast in the usual manner of making iron castings, and then treated by the usual malleableizing process.

The arm E beneath may be of other form than that shown, a shoulder of some character only being necessary.

This pole-crab is in a single piece, and produced at very much less cost than the usual method of construction, and is furnished to the trade as an article of manufacture.

I do not broadly claim a pole crab or tip formed from cast metal.

I claim as my invention—

As an article of manufacture, the herein-described carriage pole or tip, consisting of the tubular portion A, with the straps B C projecting therefrom, and the eye D formed on its forward end, and the downward-projecting holdback E, all formed in one and the same piece, from cast metal, substantially as set forth.

SAMUEL MASON.
